(57) **CLAIM**

The ornamental design for a display screen with animated graphical user interface, as shown and described.

DESCRIPTION

FIG. 1 is a front view of the first image in the sequence for a display screen with animated graphical user interface of a first embodiment showing our new design;

FIG. 2 is a front view of the second image thereof;

FIG. 3 is a front view of the third image thereof;

FIG. 4 is a front view of the fourth image thereof;

FIG. 5 is a front view of the fifth image thereof;

FIG. 6 is a front view of the sixth image thereof; and

FIG. 7 is a front view of the seventh image thereof.

FIG. 8 is a front view of the first image in the sequence for a display screen with animated graphical user interface of a second embodiment showing our new design;

FIG. 9 is a front view of the second image thereof;

FIG. 10 is a front view of the third image thereof;

FIG. 11 is a front view of the fourth image thereof;

FIG. 12 is a front view of the fifth image thereof;

FIG. 13 is a front view of the sixth image thereof; and

FIG. 14 is a front view of the seventh image thereof.

FIG. 15 is a front view of the first image in the sequence for a display screen with animated graphical user interface of a third embodiment showing our new design;

FIG. 16 is a front view of the second image thereof;

FIG. 17 is a front view of the third image thereof;

FIG. 18 is a front view of the fourth image thereof;

FIG. 19 is a front view of the fifth image thereof;

FIG. 20 is a front view of the sixth image thereof; and,

FIG. 21 is a front view of the seventh image thereof.

The outer most broken line square shows a display screen and forms no part of the claimed design. All other broken line is for the purpose of illustrating portions of the graphical user interface and forms no part of the claimed design.
